UNITED STATES PATENT OFFICE.

ROBERT HENKE, JR., OF NEW YORK, N. Y.

PAINT-CAN.

933,444.

Specification of Letters Patent. Patented Sept. 7, 1909.

Application filed May 19, 1909. Serial No. 496,898.

To all whom it may concern:

Be it known that I, ROBERT HENKE, Jr., a citizen of the United States, residing at New York city, Brooklyn, county of Kings, State 5 of New York, have invented new and useful Improvements in Paint-Cans, of which the following is a specification.

This invention relates to a can of novel construction which will segregate the liquid 10 and solid constituents of marine or other paint, and will permit said constituents to be readily intermixed when the paint is to be used.

In the accompanying drawing: Figure 1 15 is a vertical central section of my improved paint can; Fig. 2 a similar section of the inner receptacle, showing it reversed; Fig. 3 a similar section of the outer receptacle, showing it reversed, and Fig. 4 a plan of 20 Fig. 1.

The can is composed of an outer receptacle 10 adapted to contain the liquid constituent of the paint, and of an inner receptacle 11 extending axially through the outer receptacle and adapted to contain the bronze 25 powder or other solid constituent of the paint.

The bottom 12 of the outer receptacle is provided with an upwardly extending bulge 30 13 which is preferably centered on the bottom. At its top, outer receptacle 10 is provided with an annular head 14 having a depending flange 15, the diameter of the opening formed within head 14 being greater 35 than the diameter of bulge 13.

Inner receptacle 11 is provided at its lower open end with a foot 16 adapted to rest upon bottom 12, and with an inwardly extending flange 17 adapted to snugly encompass 40 bulge 13. At its top, inner receptacle 11 is permanently closed by a laterally extending head 18 having upwardly bent circumferential flange 19 adapted to frictionally engage the flanged edge 15 of head 14. 45 It will be observed that head 18 extends partly over the annular chamber 20 formed between receptacles 10, 11, so that said chamber is closed by the co-operation of heads 14, 18. Within the overhanging portion of head 50 18 is formed a filling orifice 21, which thus communicates with chamber 20. This opening may be closed by a suitable covering plate or similar device 22.

To fill the can, inner receptacle 11 is reversed, (Fig. 2), and the bronze powder or

other solid component of the paint is poured into the same. Outer receptacle 10 is also reversed, (Fig. 3), and projected over the inner receptacle, so that bulge 13 of the former will be tightly grasped by the flange 60 17 of the latter, while heads 14, 18 will become simultaneously interlocked by a slip joint. The receptacles being thus connected, are righted and the liquid component of the paint is poured into chamber 20 through 65 orifice 21, after which said orifice is sealed, so that the can is ready for the market.

If the paint is to be used, head 18 is pried loose from head 14 and then the inner receptacle is lifted out of the outer receptacle. 70 While the inner receptacle is thus raised, its contents will be discharged into the outer receptacle, so that the two constituents of the paint will become readily mixed.

It will be seen that my improved can 75 effectively separates the two elements constituting the paint and that such elements are brought together in a most simple manner when the can is opened.

I claim:

1. In a paint can, an outer receptacle having a bottom bulge, combined with an inner receptacle extending axially through the outer receptacle and having an open lower end adapted to removably engage said bulge. 85

2. In a paint can, an outer receptacle having a bottom bulge, combined with an inner receptacle extending axially through the outer receptacle and having an open lower end, and a flange within said end adapted 90 to removably grasp said bulge.

3. In a paint can, an outer receptacle having a bottom bulge and an annular head, combined with an inner receptacle adapted to engage said bulge and having a laterally 95 extending head adapted to frictionally engage the head of the outer receptacle.

4. In a paint can, an outer receptacle having a bottom bulge, combined with an inner receptacle adapted to engage said bulge and 100 having a laterally projecting apertured head of greater diameter than said bulge and extending into engagement with the outer receptacle.

Signed by me at New York city, (Man- 105
hattan,) N. Y., this 18th day of May, 1909.

ROBERT HENKE, JR.
